UNITED STATES PATENT OFFICE.

HARRY C. LANGER, OF MILWAUKEE, WISCONSIN.

STOCKING AND METHOD OF MAKING.

Application filed October 20, 1924. Serial No. 744,788.

To all whom it may concern:

Be it known that I, HARRY C. LANGER, a citizen of the United States, and resident of Milwaukee, in the county of Milwaukee and State of Wisconsin, have invented certain new and useful Improvements in Stockings and Methods of Making; and I do hereby declare that the following is a full, clear, and exact description thereof.

10 This invention relates to full-fashioned stockings and to the method of knitting such stockings. Full-fashioned stockings are knit upon straight knitting machines and, as is well known, it is the customary 15 practice to knit the stocking on two separate machines known as the "legger" and the "footer", necessarily requiring transferring from one machine to the other. In this operation of transferring, it is clear that a 20 slight error will produce a second or defective stocking and that a slight difference in the exact shade or quality of the body threads used in the two machines will also produce a second. Further than this, the 25 transferring requires skilled labor and produces a considerable loss of time in the production of full-fashioned stockings.

This invention is designed to overcome the 30 above noted defects and objects of such invention are to provide a method of knitting full-fashioned stockings in which the production of seconds is eliminated, and in which skilled labor and loss of time due to transferring is wholly avoided.

35 More specifically this invention has for its object to provide a method of knitting full-fashioned stockings upon a straight knitting machine which requires no transfer nor change of main body threads, and which 40 continuously knits the leg and instep portion of the stockings without any line of demarkation, and which knits all portions of the stocking upon the same machine.

45 Further objects are to provide a full-fashioned knit stocking which has no line of demarkation between the leg portion and the instep portion, in which the instep portion is knit as an integral continuation of the leg portion, in which heel tabs are knit 50 as a continuous portion of the foot portion of the stocking, and in which the vertical side seams adjacent the heel portion are avoided.

55 The drawing illustrates various stages in the knitting of the stocking in a diagrammatic manner.

In the drawing Figure 1 shows the body portion or leg portion of the stocking knit down to adjacent the instep portion.

Figure 2 shows dropped stitches on the 60 side portions of the leg of the stocking and shows the central stitches temporarily held upon the needles.

Figure 3 shows the heel tabs as they appear in their relative positions in the knitting of the stocking.

Figure 4 shows dropped stitches on the knitting of the leg portion and instep portion and foot portion.

Figure 5 is a view corresponding to Figure 4 showing in imaginary lines the outline 70 of the complete foot portion.

Figure 6 shows a further stage in the production of the stocking in which the heel tabs have been looped to the leg portion.

Figure 7 is a side elevation of the completed stocking.

The term "stocking" is employed in its most generic sense throughout this case and is used to avoid needless repetition.

In practising the method contemplated by this invention the leg portion 1 is knit in the usual manner upon a straight knitting machine and is narrowed, as indicated at 2, until the line 3 is reached. At this point a loose row is knit in from opposite sides of the stocking towards the center, such loose rows being indicated at 4 in Figure 2.

When the knitting has progressed to the stage indicated in Figure 2, the central portion of the stocking as indicated at 5, is buried beneath the knock-over bits, and the sides are thrown off, as indicated at 6, on opposite sides of this central portion.

It is to be noted that when the central portion 5 is buried beneath the knock-over bits that knitting at this point temporarily ceases. The machine is again started and the heel tabs 7 are knit, as indicated in Figure 3, and are formed on the machine by the same needles which held the cast off portions 6. It is to be noted that the heel tabs gradually widen, as indicated at 8, and this widening is done by means of selvage dividers and widening out the machine.

When the knitting of the heel tabs has progressed for a sufficient period to provide the necessary length of heel tabs, the central portion indicated at 5 in Figure 2 is lifted above the knock-over bits and knitting then progresses from one side to the

other side edge 9, as indicated in Figure 4, thus forming an instep portion 10 continuous and integral with the leg portion 1. The same thread employed in forming the leg portion is employed in forming the instep portion 10 and the same thread or threads in forming the heel tabs 7 are used to form the side portions 11 of the foot of the stocking. This process continues until the requisite length of foot is approached then narrowing takes place, as shown in Figure 5, and a complete foot portion results.

It is to be noted in connection with the formation of heel tabs that a loose row, as indicated at 12, is knit into the heel tabs adjacent their first formed edges. The next stage in the manufacture of this stocking is indicated in Figure 6, in which the heel tabs 7 have been turned outwardly. The portions 6 (see Figure 2) of the leg portion are ripped out down to the loose rows 4. The lateral edges 13 of the heel tabs are marked along a lateral row preferably the second row from the edge, such marking consisting essentially in widening the row by a suitable tool for the purpose of looping. Thereafter, the lateral edges 13 of the heel tabs, (see Figure 5) are looped along these marked rows to the shouldered portions of the leg 1 formed at the loose rows 4. The stocking is then folded and the first knit portions of the heel tabs are ripped out down to the loose rows 12 and looped together, and the stocking is seamed in the usual manner to produce the complete stocking illustrated in Figure 7. If desired a rear reenforce 14 may be produced in the leg portion and the appropriate portions of the heel tabs in the usual manner, as indicated in imaginary lines in Figure 7.

It is to be understood that the gradual widening of the heel tabs, as illustrated in Figure 3, and indicated by the reference character 8, may be formed by other means than by the use of selvage dividers. For example, the heel tab may be shaped by a more tightly knit portion merging into a gradually looser knit portion. Further the shaping may be done by what is known as decking. If, however, it is not desired to shape during knitting, obviously, the shape of the heel tab, as indicated at 8, may be produced by knitting a heel tab of uniform width and sewing it round and thereafter cutting off the corner portions to provide the necessary taper.

It will be seen from this detailed description that a method has been provided which permits the continuous knitting of the instep with the body portion or leg portion 1, and without removing the stocking from the machine and without employing the process of transferring.

It will further be seen therefore that no

line of demarcation is formed between the leg portion and instep portion but that a continuously knit instep portion is provided without any possible chance of the formation of seconds due to errors in this portion of the work.

It is further to be noted that the side seams adjacent the heel have been avoided as the heel tabs are knit integral with the foot portion and as the line of looping extends horizontally, as indicated in Figure 7 by reference character 15.

It is to be noted, therefore, that a much more attractive full-fashioned stocking has been produced than has heretofore been possible, and that by the use of the method detailed herewith the service of skilled operators for transferring is wholly dispensed with, and consequently the expense of production has been reduced and the speed with which the stockings are formed has been increased.

Although the invention has been described in considerable detail, it is to be understood that the invention may be variously embodied and is, therefore, to be limited only as claimed.

I claim:

1. The method of knitting a blank for a full-fashioned stocking comprising knitting the leg portion to the instep, throwing off stitches on opposite sides of the central instep, burying the central instep portion below the knock-over bits of the knitting machine, knitting heel tabs, and thereafter raising the buried central portion of the instep and knitting straight across the heel tabs and the central instep to form the foot portion.

2. The method of knitting a blank for a full-fashioned stocking comprising knitting the leg portion to the instep, throwing off stitches on opposite sides of the instep, holding the stitches at the central portion of the instep, knitting heel tabs positioned on opposite sides of the central instep portion until tabs of sufficient length have been formed, and thereafter knitting straight across said heel tabs and said central instep portion.

3. The method of knitting a blank for a full-fashioned stocking upon a straight knitting machine having needles and knock-over bits, said method comprising knitting the leg portion to adjacent the instep, throwing off stitches on opposite sides of the central portion of said instep, burying the central portion of said instep below the knock-over bits and holding the stitches upon the needles, knitting heel tabs upon opposite sides of the central instep portion until the requisite length has been secured, raising the buried central instep portion, and knitting straight across said heel tabs and the central instep portion.

4. The method of making a full-fashioned stocking comprising knitting the blank on a straight knitting machine by first knitting the leg portion to adjacent the instep, throwing off stitches on each side of the central instep portion, holding the stitches at the central instep portion, knitting heel tabs located on each side of the central instep portion until the requisite length of tabs has been secured, thereafter knitting straight across the said heel tabs and the central instep portion to form the foot portion of the stocking, turning the heel tabs laterally and looping such tabs to the leg portion on opposite sides of the central instep portion, 15 and seaming the outer edges of the foot and leg portion to form a finished stocking.
- In testimony that I claim the foregoing I have hereunto set my hand at Milwaukee, in the county of Milwaukee and State of Wisconsin. 20

HARRY C. LANGER.
